UNITED STATES PATENT OFFICE.

JOHN ARTHUR KAYE, OF SAULT STE. MARIE, WEST ONTARIO, CANADA.

BERRY-PICKER.

1,283,526.

Specification of Letters Patent.

Patented Nov. 5, 1918.

Application filed May 6, 1918. Serial No. 232,885.

To all whom it may concern:

Be it known that I, JOHN ARTHUR KAYE, a subject of the King of Great Britain, residing at Sault Ste. Marie, in the Province of West Ontario, Dominion of Canada, have invented a new and useful Berry-Picker; and I do hereby declare the following to be a full, clear, and exact description of the invention, such as will enable others skilled in the art to which it appertains to make and use the same.

The present invention relates to certain new and useful improvements in berry pickers, and has for its object to provide a device of this character which embodies novel features of construction whereby blue-berries and the like may be readily taken from the bushes and collected in a receptacle.

Further objects of the invention are to provide a berry picker of this character which is comparatively simple and inexpensive in its construction, which eliminates the tiresome stooping-over which is incident to hand picking of the berries, which separates dust and sand from the berries as they are picked, and which can be easily taken apart for cleaning.

With these and other objects in view, the invention consists in certain novel combinations and arrangements of the parts as will more fully appear as the description proceeds, the novel features thereof being pointed out in the appended claims.

For a full understanding of the invention, reference is to be had to the following description and accompanying drawing, in which:

Figure 1 is a top plan view of a berry picker, constructed in accordance with the invention.

Fig. 2 is a side elevation of the same, parts being shown in section.

Fig. 3 is an enlarged transverse sectional view through the hollow body of the berry picker taken on the line 3-3 of Fig. 1.

Fig. 4 is a top plan view of the lower section of the berry picker.

Corresponding and like parts are referred to in the following description and indicated

in all the views of the drawings by the same reference characters.

Referring to the drawings, which illustrate one embodiment of the invention, the numeral 1 designates the hollow body of the picker, said body being provided at its forward end with a series of spaced fingers 2, and at its rear end with tapered necks 3 which discharge into a receptacle 4. The hollow body is divided horizontally into upper and lower complemental sections, 1^a and 1^b respectively, the sections being provided at their sides with corresponding ears 5 which are detachably connected by suitable fastening members such as the bolts 6. The fingers 2 are secured at their rear ends to the ends of conical projections or noses 7 at the forward edge of the body 1, and the top of the body is provided with a series of openings 8, and surrounded at the back and sides thereof by a guard flange 9. The berries which are separated from the bushes by drawing the fingers 2 through the same are deflected to the top of the body 1 and pass through the openings 8 into the interior of the body. From the interior of the body the berries are discharged rearwardly through the tapered necks 3 into the funnel-shaped cover 10 of the receptacle 4.

The interior of the hollow body 1 is preferably sub-divided into two compartments by a longitudinally extending partition 11, and the bottoms of these compartments are provided with large openings across which fine screens 12 are stretched, said screens being clamped in position by means of the frames 13. All dust and sand is thus separated from the berries before they are discharged into the receptacle 4, the dust or sand falling through the screens while the berries pass rearwardly through the necks 3 and are directed by the funnel-shaped cover 10 into the receptacle 4.

A handle 14 extends rearwardly from the body 1, having the forward end thereof curved downwardly at 14^a and fitted into a ferrule 15 which is integral with the rear end of the body. This handle 14 carries both the body 1 and the receptacle 4, and

the latter is preferably clamped detachably in position so that it can be removed whenever desired. A hooked arm 16 extends downwardly from the bottom of the body 1, 5 the upper end of the arm being hinged at 17 to the body, while the lower end thereof is hooked at 16^a and adapted to engage one of a pair of depressions 18 formed in the bottom of the receptacle. A longer arm 19 10 has the upper end thereof hingedly connected at 20 to the handle 14, the lower end of the arm being hooked at 19^a and adapted to engage the other one of the depressions 18 in the bottom of the receptacle. A slide 15 21 is adjustable upon the arm 19 and formed with a finger 22 which is adapted to engage the edge of the cover 10 and coöperate with the hooked end 19^a of the arm to clamp the receptacle in position. A set screw 23 is 20 provided for locking the slide 21 in an adjusted position. It will thus be obvious that the receptacle 4 is held rigidly in position while the berry picker is in use, although it can be readily removed whenever desired. 25 The bottom of the receptacle 4 is provided with an outlet opening 24 which is normally closed by a cap 25. When the receptacle has been filled or partially filled with berries, the cap 25 is removed and the berries 30 discharged into a suitable container provided for the purpose.

Having thus described the invention, what I claim as new and desire to secure by Letters Patent, is:—

35 1. A berry picker including a handle, a hollow body carried by the handle and having a perforated top and a discharge neck leading from the interior thereof, a series of picking fingers projecting from one end 40 of the body, and arranged to deliver berries upon the top of the body, and a receptacle carried by the handle and arranged to receive the berries from the discharge neck of the body.

45 2. A berry picker including a handle, a hollow body carried by the handle, said body having a perforated top through which the berries enter its interior, and a discharge neck leading from the body, a 50 screen at the bottom of the body for separating dust from the berries, a series of fingers projecting from one end of the body and arranged to deliver berries upon the perforated top, and a receptacle carried by the handle and arranged to receive the berries from the discharge neck.

55 3. A berry picker including a handle, a hollow body carried by the handle and having a perforated top through which berries 60 enter the interior of the body and a discharge neck leading from the body, a series of picking fingers projecting from the forward end of the body and arranged to deliver berries on the perforated top thereof,

a guard flange projecting upwardly from 65 the body and extending around the back and sides thereof, and a receptacle carried by the handle and arranged to receive the berries from the discharge neck.

4. A berry picker including a handle, a 70 flattened hollow body carried by the handle and having a perforated top through which the berries enter the body and a discharge neck leading from the body, said body being divided horizontally into separable complementary sections, a series of picking fingers projecting from one end of the body and arranged to deliver berries upon the perforated top of the body, and a receptacle carried by the handle and arranged to 75 receive the berries from the discharge neck.

5. A berry picker including a handle, a flattened hollow body carried by the handle and having a perforated neck through which the berries enter the body and a discharge neck leading from the back of the body, said body being divided horizontally into upper and lower separable sections, a series of picking fingers projecting from the front of the body and arranged to deliver 85 berries upon the perforated top thereof, the picking fingers being carried by one section of the body while the discharge neck is carried by the other section, a guard flange extending around the back and sides of the 90 top, and a receptacle carried by the handle and arranged to receive the berries from the discharge neck.

6. A berry picker including a handle, a hollow body carried by the handle and constructed with a perforated top and a discharge neck, a series of picking fingers projecting from one end of the body and arranged to deliver the berries to the top of the body, depending arms carried by the 105 body and handle, and a receptacle supported by the depending arms and arranged to receive berries from the discharge neck of the body.

7. A berry picker including a handle, a hollow body carried by the handle and formed with a perforated top and a discharge neck, a series of picking fingers projecting from one end of the body and arranged to deliver berries upon the perforated top thereof, hooked arms dependent from the body and handle respectively, a receptacle supported by the hooked arms and arranged to receive the berries from the discharge neck, and means for clamping the 110 receptacle in position.

8. A berry picker including a handle, a hollow body carried by the handle and formed with a perforated top and a discharge neck, a series of fingers projecting 115 from the end of the hollow body and arranged to deliver berries upon the perforated top thereof, dependent hooked arms

hingedly connected at their upper ends to the body and handle respectively, a receptacle formed with depressions which are engaged by the hooked ends of the arms, and holding means for holding the receptacle in position upon the arms, said receptacle receiving the berries from the discharge neck.

In testimony whereof I have signed my name to this specification in the presence of two subscribing witnesses.

JOHN ARTHUR KAYE.
